DEODORANT AND TOILET CONTAINER

Roy Theodore Clarence Castrique, South
Melbourne, Victoria, AustraliaApplication May 12, 1939, Serial No. 273,247
In Australia July 27, 1938

4 Claims. (Cl. 312—31)

The object of this invention as its title implies has reference to the deodorizing of the air and the toilet paper in lavatories, hospital wards, sick rooms, and such like confined places.

5 Hitherto it has been the accepted practice to freely distribute disinfectants in and about such localities and also, when desirable, to impregnate such papers prior to filling same into the container, but it is well known that such disinfectants very quickly disperse into and from the air and thus lose their effectiveness thus making it essential to redisinfect same, resulting in considerable loss thereof.

10 The main object of the invention, therefore, is to overcome this disadvantage and to provide means whereby the disinfecting deodorant, while effecting to useful purpose will also have a maximum life.

15 With the above object in view, said invention resides in the means employed whereby same is carried into practical effect.

An important feature of the invention resides in the utilisation of a separate compartment fitted within or fixedly or removably secured to 20 the toilet paper container, which latter and said separate container as a unit is anchored by screws to the wall of the lavatory or on a standard or on any other suitable fixture, and is also adapted to be locked against inadvertent and 25 unauthorized opening.

Within the said separate container is placed the deodorant or disinfectant same preferably being in tablet, pilule or lozenge form.

30 A further feature of the invention resides in the means employed whereby the perfume from said deodorant or disinfectant, tablets, pilules or lozenges, are adapted to permeate and impregnate the toilet papers within the adjacent container and also to disperse within the air of the lavatory, sick room, hospital ward or other like confined localities, thus always maintaining same in a sweetened condition for the overcoming of disagreeable odours and such like.

35 A still further feature of the invention resides in the means employed for the removability of the deodorant compartment from the paper or main container. Although principally usable in lavatories, it will also be readily appreciated that the herein invention is usable and is highly advantageous in hospital wards, sick rooms and such like rooms and localities where disagreeable odours are prevalent as above mentioned.

40 In order, however, that the invention may be 45 more fully understood the construction of the

same will be described with the aid of the accompanying drawing wherein:

Figure 1 is a perspective view of the said invention in the closed position and as anchored to a wall or other fixture. 5

Figure 2 is a similar anchored and perspective view showing said invention in the open position.

Figure 3 is a sectional view on the line 3—3 of Figure 1.

Figure 4 is a perspective view of the removable deodorant container, compartment or holder. 10

Referring to the said drawing—

I employ a container, made for example, of sheet metal, and of a box-like form and shape, 15 same being of approved and suitable dimensions. This container comprises companion sections 10—11 fitted and connected together by hinges or such like free pivotal means as 12.

One of the said sections as 10 is, by screws, 20 bolts or studs 13, adapted to be anchored, for example, at a convenient position on and to the inner wall 14 of the lavatory or on and to a standard or other fixture as may be convenient.

Within the said anchored section 10, and to 25 one end thereof, is freely and snugly fitted a removable compartment or holder 15, same being detachably secured therein by bracket 16, spring clips 17 and/or the like so as to retain same in operative and usable position. 30

The outer wall of the said compartment or holder 15 is made or provided with a gap or slot 18 to coincide with and freely fit over the adjacent hingeable pivot pin 12 thus occupying the full available space within the main container. 35

This compartment or holder 15 carries and holds the aforementioned deodorant tablets, pilules, lozenges or other disinfectant or air sweetening and disagreeable odour dispersing 40 means.

The outer walls of the said compartment or holder 15 are made with perforations or slots 19 wherethrough issues the perfume from the said tablets, pilules, lozenges or other disinfectant. 45

These perforations or slots 19 coincide with perforated or slotted formations 20, made and provided in the adjacent walls of the companion hinged section 11 of the main container, 50 when the whole is in the closed operative position. This allows of the perfume from the said deodorant or disinfectant to have a free passage from the container into the outer and surrounding atmosphere for the sweetening of same 55

against, and dispersing and/or overcoming disagreeable odours.

Within the aforesaid anchored section 10 of the main container is also fitted the usual rollers 22 which are mounted in the bracket 16.

5 The latter are also adapted to be perfumed and deodorized or disinfected by the aforesaid tablets, pilules, lozenges or other means, said perfume being dispersed through perforations or slots 23 in the compartment wall of the deodorant container, adjacent said paper compartment, and 10 also from around the said adjacent wall.

When charged with paper and deodorant or disinfectant as above set forth, the container as a whole is adapted by lock 24 to be closely sealed against inadvertent or unauthorized opening.

It will thus be seen from the foregoing that by this invention I provide a combined and/or detachably connected deodorant (or disinfectant) and toilet paper container which, by its construction, enables the said toilet paper and also the outer atmosphere within lavatories, hospital wards and sick rooms or such like confined spaces or localities to be perfumed. This perfuming of the papers and atmosphere thereby overcomes all disagreeable odours, and maintains such atmosphere always in a sweetened, healthy and clean condition, and which it is well known is essential, especially in sick rooms, hospital wards and such like as hereinbefore set forth.

30 I do not wish to be arbitrarily confined to the hereinbefore described details, since I may if necessary have to depart therefrom, and while I have described the essential characteristics of my invention, I desire it to be understood that various and suitable modifications may be made therein without departing from the spirit, scope and ambit of the invention.

40 I claim: 1. A container of the class described, comprising a stationary and a movable section, said latter section being provided with a plurality of slots at each end of said section, a bracket removably secured in said stationary section, said bracket having an upstanding flange at each end thereof, one of said flanges being so disposed with reference to one side of said section as to define a channel, a removable compartment adapted to be secured in said channel and being of less height than the height of said stationary section, said compartment comprising a pair of side walls, said side walls being joined at one

the following table, which gives the number of cases of each disease, the number of deaths, and the percentage of mortality for each disease, and the percentage of the total number of cases of all diseases to the total number of cases of all diseases.

side by a third wall, one of said side walls and said third wall having a plurality of openings, and means for securing said compartment to said bracket.

2. A container of the class described, comprising a casing having a stationary and a movable section, said movable section being pivotally secured to said stationary section, said latter section being provided with means for securing said section to a support, a bracket mounted in said stationary section having an upstanding flange at each end thereof, the end wall of said stationary section and one of said upstanding flanges defining a channel, a compartment adapted to be secured in said channel, said compartment comprising a pair of side walls joined at one of its edges by a third wall, a plurality of openings in one of said side walls and said third wall, means for securing said compartment to said bracket, and slots in said movable section at each end thereof, the slots at one end corresponding to the openings in said compartment whereby air may pass from said container and said compartment and into the atmosphere and back into the container through said group of slots at opposite end of said section. 20

3. A container of the class described, comprising a main casing divided into two companion sections, a plurality of slots at each end of one of said companion sections, a bracket mounted upon the other of said companion sections having an upstanding flange at each end thereof, a channel formed between said bracket and one end of said companion section, a U-shaped compartment mounted in said channel and adapted to hold a supply of deodorant, said compartment having a plurality of openings therein, said openings corresponding to the openings at one end of said companion section, and means for securing said compartment to said bracket. 30 35 40

4. A container of the class described, comprising a stationary section housing having a companion section pivotally secured thereto and embracing said stationary section, characterized by a bracket within said stationary section, an up-standing lip made integral with said bracket and spaced from a companion lip at one end of the floor of the stationary section of said casing, a U-shaped compartment removably disposed between said lips and means to secure said compartment to one of said lips. 45 50
